(57) **CLAIM**

The ornamental design for a case for toy beads, as shown and described.

DESCRIPTION

FIG. 1 is a front, top, and right perspective view of a case for toy beads showing my new design;

FIG. 2 is a rear, bottom, and left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is a perspective view of the case for toy beads and shown in an alternate configuration with a lid and another case for beads.

The broken lines showing of a lid and another case for beads depict environmental structure and form no part of the claimed design.

1 Claim, 9 Drawing Sheets
